BALL REPROJECTOR

Pat La Rock, Chicago, Ill., assignor, by mesne assignments, to Chicago Coin Machine Co. (not inc.), Chicago, Ill., a copartnership composed of Samuel Gensberg, Dora Gensberg, Samuel Wolberg, and Eva Wolberg

Application July 10, 1941, Serial No. 401,712

3 Claims. (Cl. 273—85)

This invention relates to certain novel improvements in amusement game apparatuses and has for its principal object the provision of an improved construction of this character which will be highly efficient in use, and one which will afford the maximum amount of amusement.

Among the salient objects of this invention is the provision in an amusement game apparatus of two or more oppositely disposed manually controlled manikins whereby upon the operation individually of the manikins a ball may be propelled across a playing field. The present invention particularly relates to a game of hockey, although the invention is not to be limited to such game.

Other objects will appear hereinafter.

The invention consists in the novel combination and arrangement of parts to be hereinafter described and claimed.

The invention will be best understood by reference to the accompanying drawings showing the preferred form of construction, and in which:

Fig. 1 is a perspective view of the invention; Fig. 2 is a fragmentary sectional detail view taken substantially on line 2—2 of Fig. 1;

Fig. 3 is a plan sectional detail view of the invention taken substantially on line 3—3 of Fig. 1;

Fig. 4 is a fragmentary sectional detail view of the same taken substantially on line 4—4 of Fig. 1;

Fig. 5 is an illustration, partly in perspective, of the mechanism for controlling the operation of the manikins embodied in the invention;

Fig. 6 is a diagrammatical view of an electric circuit controlling the ball elevator embodied in the invention; and

Fig. 7 is an electrical diagram of the scoring circuit employed in my invention.

In the drawings I have illustrated the preferred form of construction of my invention. In this connection the invention comprises a cabinet 10 within which is arranged a playing board 11 beneath a glass panel 12. From a medial line indicated at 13 the playing board is inclined downwardly in opposite directions. However, I do not desire to be limited to this specific structure since the playboard 13 is equally effective when inclined from the front to the extreme rear whereby all balls will gravitate to the front end of the cabinet. Each end 14 of the playing board 13 terminates into a ball return trough 15 having communication with an auxiliary return runway 16 communicating with a ball elevator passage 17. Balls are elevated upwardly through this passage 17 by a ball elevator 18 comprising an arm 19 pivotally supported at 20 to a wall of the cabinet 10 and in-

cluding a depending finger 21 adapted to be engaged by a cam 22 fixedly mounted upon a rotatable shaft 23 of an electric motor 24. This motor 24 is in an electric circuit 25 including a source of electric energy 26 and a time switch 27 of a well-known type.

This time switch is operated by means of the coin slide 28 of a coin control mechanism 29, the arrangement being such that upon inward movement of the coin slide 28 the inner end 30 thereof will engage an arm 31 having connection to the time switch as at 32, and movement of this arm 31 will set the time switch into operation for controlling the circuit 25 of the motor 24, which motor

will be conditioned for operation pending the control of the circuit 25 by such time switch. An additional switch 67 is mounted on the underside of the transverse portion 16' of the auxiliary return runway 16 and has one contact element

20 thereof extending up into the path of travel of the balls for engagement thereby to cause such contact element to close circuit through the other or complementary contact element. The arrangement is such that circuit to the motor 24 is completed when a ball is in the runway 16' and such that when the last ball passes out of engagement with the switch contact disposed in the runway 16' circuit will be broken at the switch 67 to stop the motor 24.

30 The entrance to each return trough 15 comprises a goal including a ball-actuated gate 33 pivotally supported as at 34 to a portion of the cabinet 10. This gate 33 has an arm 35 which is adapted to close an electric switch 36 of a score element 37. There are two separate score indicators, one for the switch 36 in the front trough and another for the switch 36 of the rear trough.

35 Each indicator in the score circuit 37 includes a series of electric bulbs 38, illumination of which is controlled by a step-up commutator switch 39 of a well-known structure and including an electromagnet 68, the switch 39 being operative in step-by-step fashion through the medium of the electromagnet 68 each time the switch 36 with which it is connected is closed, and the switch 36 is closed each time a ball gravitates through the entrance opening to the return runway 15.

40 Mounted at opposite ends of the playing board 11 adjacent the entrance to the return trough 15 is a manikin 40 including a bat or other ball propelling instrument 41 disposed for movement substantially parallel with the surface of the playing board 11. This manikin is mounted upon a shaft 42 and includes an enlarged base 43 which serves to support the shaft in the position

shown. The shaft 42 has operative connection with a train of gears 44, the pinion 45 of which is mounted upon a shaft 46 of a reversing motor 47. The motor 47 is in electric circuits 48 and 48' and these electric circuits are under the control of stationary contact plates 49 and 49' and a movable contact pin 50. The stationary contact plates 49 and 49' are carried by a fixed panel 51 supported by a ball of the cabinet 10. The contact pin 50 is movable with an arm 52 normally retained in a central position with respect to the panel 51 by a centering spring 53, one end 54 of which is connected to the arm 52 and the opposite end 55 to the underside of the playing board 11 as shown in Fig. 4.

The arm 52 is fixed to the shaft 56, one end 57 of which extends exteriorly of the cabinet 10 with bearings in a suitable plate 58. A handle 59 is provided and this handle is connected to the shaft 57 as at 60, whereby upon oscillation of the handle 59, the plate 52 will oscillate for reasons hereinafter set forth.

Arranged in the auxiliary return trough 16 are cut-off pins 61, there being one of such pins 61 adjacent each of the return troughs 15, each pin 61 being slidably supported by bracket formations 62 on trough 15 and having end portions 63 connected to a bell crank 64 in turn connected to a spring-controlled bar 65 carrying the arm 31. The arrangement is such that when the bar 65 is permitted to return to its normal position under the action of the spring 66, the cut-off pins 61 will be moved into blocking position into the return runway 16, thus blocking gravitation of the balls to the elevator 18.

The game is played as follows:

The operator deposits a coin in the coin slide and moves the slide 23 inwardly. The slide will thereupon engage the arm 31, set the timing switch into operation, move the bar 65 in a direction to dispose the ball blocking pins from ball blocking position. This permits the balls to roll down the return runway to the elevator where the weight of a ball will close circuit through switch 67, and as the motor 24 is now operating, these balls will be successively elevated up the ball passage 17, through an outlet opening 17' onto the playing board 11. Upon rolling onto the playing board 11, the ball will gravitate toward the front end of the machine. It will therefore be the object of the player to manipulate the manikin at that end of the machine so as to bring the ball-striking bat into contact with the ball and project the same toward the rear or other end of the machine. If this is accomplished, it will then be the object of the player to manipulate the manikin at the rear end of the machine so as to bring the ball-striking bat thereof against the ball to return the ball to the first manikin. This operation continues until the ball is missed and passes into either one of the ball return troughs 15. In passing into the troughs 15 the switch 36 associated therewith will be closed by the gate 34 and the step-up switch 39 caused to operate to illuminate one of the lamps 38 to indicate a score for the successful play, it being pointed out that there are two rows of electric lamps 38 to indicate into which of the return runways 15 the ball has passed and that a separate score will be recorded for each of the goals.

The two manikins are alike in structure and each includes a motor unit 47R which will rotate the shaft 46 in a right-hand direction (clockwise) and a motor unit 47L which will rotate

shaft 46 in a left-hand direction (anticlockwise). The motor unit 47R is in the circuit indicated at 48 having connection with contact member 49' on the fixed panel 51 and the motor unit 47L 5 is in the circuit 48 which includes the contact 49 as a part of its control switch.

The manipulation of these manikins takes place through the operation of the handle 59, which is accomplished by oscillating the handle 10 back and forth so as to bring the contact 50 into engagement with either the contact member 49 or the contact member 49' to complete either circuit 48 or 48' as the case may be, and thus cause the operation of the motor according to the 15 direction of rotation desired for ball striking purposes. In other words, pivoting the handle 59 to the right will cause both manikins to operate in a clockwise rotation, whereas pivoting the handle to the left will cause the operation of the 20 manikins in an anticlockwise rotation.

The appeal of the game is enhanced by reason of the two manikins operating simultaneously, since the person playing the game, while attentive to the action of the foremost manikin, for 25 the moment, is not aware of the activity of the rearmost one and he is called upon to exercise his skill in manipulation of the handle 59 in order to prevent the rearmost manikin from obstructing the movement of the ball to successfully build 30 up a score in the rearmost goal or ball trap 15.

Thus, it will be seen that the two manikins are under the complete control of the player and that whether or not the ball or balls find lodgement in the desired return runways will depend upon 35 the skill of the operator in preventing the ball by means of these manikins from so entering the return runways as well as controlling the manikins to direct the ball toward a desired runway. Thus, it is apparent that I have provided a game which 40 requires the skill of the operator in arriving at a proper score. The game presents a maximum amount of amusement, as well as skill.

While I have illustrated the game apparatus as being coin-controlled, it is obvious that the same 45 may be so arranged as to be played without the use of a coin. This may be accomplished by providing a control slide without a coin aperture.

While I have illustrated and described the preferred form of construction for carrying my invention into effect, this is capable of variation 50 and modification without departing from the spirit of the invention. I therefore do not wish to be limited to the precise details of construction set forth, but desire to avail myself of such 55 variations and modifications as come within the scope of the appended claims.

Having thus described my invention, what I claim as new and desire to protect by Letters Patent is:

1. A game apparatus of the class described comprising a playing field inclined downwardly from a transverse medial line, motor driven means for elevating a predetermined number of balls one at a time to said playing field for gravitation there-down from said elevating means toward one end only of the playing field, ball batting means at opposite ends of the playing field; means including an electric circuit for simultaneously operating said ball batting means in one direction and 60 a second circuit for simultaneously operating said ball batting means in an opposite direction and switch means including a manually operable oscillatory handle for controlling one or the other of said electric circuits whereby to reverse simultaneous operation of said ball batting means.

2. A game apparatus of the class described comprising a playing field inclined downwardly from a transverse medial line, means for elevating a predetermined number of balls one at a time to said playing field, ball batting means at opposite ends of the playing field, means for simultaneously operating said ball batting means and including an electric circuit for simultaneously operating said ball batting means in one direction and a second circuit for simultaneously operating said ball batting means in an opposite direction, switch means for each of said circuits, and a manually operated handle for optionally operating one or the other of said switch means whereby to simultaneously effect reverse operation of said ball batting means.

3. A game apparatus of the class described including a cabinet, a member within said cabinet providing a playing field inclined downwardly from a transverse medial line, means for ele- 20

vating balls one at a time to said playing field for gravitation theredown from said elevating means toward one end only of said playing field, ball batting means at opposite ends of the playing field, motor driven means for simultaneously operating said ball batting means and including separate electric circuits, one for effecting rotation of said ball batting means in one direction and the other for effecting rotation of said 10 ball batting means in an opposite direction, switch means for controlling each of said circuits, and an oscillatory handle exterior of the said cabinet and having connection with each of said switch means and adapted to be operable by the player of the game for controlling one or the other of the circuits whereby to simultaneously operate said ball batting means in one or the other of said direction of rotation at the option of the player.

PAT LA ROCK.
